[57] CLAIM

The ornamental design for a watch case, as substantially shown and described.

DESCRIPTION

FIG. 1 is a front and bottom-right perspective view of a watch showing my new design;
FIG. 2 is a left side elevational view thereof;
FIG. 3 is a right side elevational view thereof;
FIG. 4 is a top plan view thereof, the bottom plan view being a mirror image thereto;
FIG. 5 is a front elevational view thereof;
FIG. 6 is a rear elevational view thereof; and
FIG. 7 is a cross-sectional view thereof as taken from line 7—7 of FIG. 5.

FIG. 1

FIG. 2

FIG. 3

FIG. 4

FIG. 5

FIG. 6

FIG. 7
